[57] CLAIM

The ornamental design for an exterior surface configuration of a cabinet for a vehicle, as shown and described.

DESCRIPTION

FIG. 1 is a front perspective view of an exterior surface configuration of a cabinet for a vehicle showing a first embodiment of our new design;

FIG. 2 is a front left side view thereof;

FIG. 3 is a front right side view thereof;

FIG. 4 is a top view thereof;

FIG. 5 is a reduced front perspective view thereof; and,

FIG. 6 is a reduced front perspective view of an exterior surface configuration of a cabinet for a vehicle showing a second embodiment of our new design. The second embodiment is identical to that shown in FIGS. 1-5, except it is mirror symmetrical.

The rear and bottom of the cabinets form no part of the claimed design. The shelves and hardware within the cabinets shown in broken lines are for illustrative purposes only and forms no part of the claimed design. The broken line showing of the below adjacent cabinets, in FIGS. 5 and 6, depict environment and are not part of the claimed design.
